UNITED STATES PATENT OFFICE.

THOMAS C. RICHARDS, OF WINSTED, CONNECTICUT.

CANDLE-SHADE HOLDER.

No. 797,320.

Specification of Letters Patent.

Patented Aug. 15, 1905.

Application filed May 3, 1905. Serial No. 258,583.

To all whom it may concern:

Be it known that I, THOMAS C. RICHARDS, a resident of Winsted, in the county of Litchfield and State of Connecticut, have invented certain new and useful Improvements in Candle-Shade Holders; and I do hereby declare the following to be a full, clear, and exact description of the invention, such as will enable others skilled in the art to which it appertains to make and use the same.

My invention relates to an improved candle-shade holder, the object of the invention being to provide improvements of this character with improved mechanism securing the parts together, and, further, to dispense with the use of solder, making a neat and attractive device, as well as one that is strong and durable and comparatively cheap to manufacture.

With this object in view the invention consists in certain novel features of construction and combinations and arrangements of parts, as will be more fully hereinafter described, and pointed out in the claims.

In the accompanying drawings, Figure 1 is a view in elevation, illustrating my improvements. Figs. 2 and 3 are views in section, taken at right angles to each other; and Figs. 4, 5, and 6 are views illustrating details of construction.

1 represents the base-sleeve to fit the candle, which comprises a sleeve contracted at its upper end to rest on the top of the candle, flared outward, forming a flange 2 at its lower end, and made with an annular web 3 near its lower end. A collar 4 fits snugly on the sleeve 1 and is enlarged at its lower portion to receive the flanged lower end 2 of the sleeve 1, and a metal ring 5 is clamped below flange 2 by the turned-in lower end of the collar 4 to give to the holder the necessary weight and stability and add to the attractive appearance thereof.

The upright shade-supporting wires 6 are formed of one continuous wire or strip bent into semicircular form between its ends, as shown at 7, to be disposed around the sleeve 1 and clamped between an inwardly-turned flange 8 at the upper end of collar 4 and the annular web 3 on sleeve 1. The ends of these supporting-wires extend through notches in flange 8 at opposite sides of sleeve 1 and ex-

tend up alongside the sleeve 1 for a short distance and then bent outward at right angles, as shown at 9, and again bent at right angles, as shown at 10, and extend parallel upward and are secured to the shade-supporting ring 11, as will now be explained.

The ring 11 is provided in opposite sides with slits to receive tongues 12 on the side edges of clamps 13 and when bent outward on the outside of the ring secure the clamps firmly in place and prevent any pivotal or other movement thereof. These clamps 13 comprise a sheet-metal blank bent at opposite sides to receive the wires 6 and form the tongues 12, above referred to. At the lower ends of the clamps enlarged portions 14 are provided, bent at an angle and slotted to receive the wires before they enter the main body of the clamps and further secure the wires therein.

A great many slight changes might be made in the general form and arrangement of the parts described without departing from my invention, and hence I would have it understood that I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. A candle - shade holder comprising a sleeve to be inserted over the candle, a collar around the sleeve at its lower end, a weighted ring clamped between the lower end of the sleeve and the collar, and shade-ring-supporting wires secured between the collar and sleeve.

2. A candle - shade holder, comprising a sleeve to be inserted over the candle, flared outward at its lower end and having an annular web near its lower end, a collar around the sleeve, a ring clamped between the lower end of the sleeve and the turned-in end of the collar, a wire bent half-way around the sleeve and clamped between the web and a flange on the upper edge of the collar and the ends of the wire extending upward and secured to a shade-supporting ring.

3. A candle - shade holder, comprising a sleeve to be inserted on a candle, upright

wires secured to the sleeve, a shade-supporting ring having parallel slots in its opposite sides, sheet-metal clamps having tongues projecting through the slots in the ring and bent outward, enlargements on the lower ends of the clamps bent at an angle and having slots therein to receive the wires before entrance into the body portion of the clamps.

In testimony whereof I have signed this specification in the presence of two subscribing witnesses.

THOMAS C. RICHARDS.
